Reuben Edmund Weltz, Malton, Ontario, Canada

Application May 29, 1951, Serial No. 15,337

Term of patent 14 years

(Cl. D15—8)

To all whom it may concern:

Be it known that I, Reuben Edmund Weltz, a citizen of Canada, residing at Malton, Province of Ontario, Canada, have invented a new, original, and ornamental Design for a Chair, of which the following is a specification, reference being had to the accompanying drawing, forming a part thereof.

Fig. 1 is a perspective view of a chair, viewed from the front and from one side, showing my new design;

Fig. 2 is a side elevational view thereof, viewed from the other side;

Fig. 3 is a rear elevational view thereof; and
Fig. 4 is a bottom plan view thereof.

I claim:
The ornamental design for a chair, as shown.
REUBEN EDMUND WELTZ.
